UNITED STATES PATENT OFFICE.

HENRY BORN, OF CLEVELAND, OHIO.

OVEN-DOOR FOR RANGES.

SPECIFICATION forming part of Letters Patent No. 626,047, dated May 30, 1899.

Application filed February 3, 1899. Serial No. 704,361. (No model.)

To all whom it may concern:

Be it known that I, HENRY BORN, a citizen of the United States of America, and a resident of Cleveland, in the county of Cuyahoga and State of Ohio, have invented certain new and useful Improvements in Oven-Doors for Ranges, of which the following is a specification.

My invention relates to improvements in ranges, &c., and particularly to the construction and arrangement of the oven-doors thereof; and the object of my improvement is to combine strength and durability in a simple, neat, and inexpensive construction. I attain these objects in and by the construction as shown in the accompanying drawings, in which—

Figure 1 illustrates a face view of a range having a door of the kind as above alluded to. Figs. 2, 3, and 4 are detail views showing the construction of said door and the brackets supporting said door.

Like letters of reference denote like parts in the drawings and specification. Chiefly cast-iron and sheet-steel are used in the manufacture of ranges. However, for certain parts thereof, especially the pivots of the drop-doors for the ovens of such ranges, it is preëminently desirable or necessary that other material than cast-iron be used in order to withstand the slamming and jarring to which such doors are usually subjected. In selecting suitable material for this purpose I give malleable iron the preference for obvious reasons. To provide and combine suitable pivots made of this material or an equally ductile one in a durable, neat, compact, and inexpensive manner is an essential feature of my invention.

Since oven-doors are usually made up of a sheet-steel pane A and a cast-iron casing-like border B, (see Figs. 1 and 2,) I provide an anchor-plate C in connection with pivot D and interpose said plate between the pane A and hollow border B, as seen in Figs. 2, 3, and 4, which figures respectively represent inner

partial face views and a transverse sectional view of said door. At a the door-border flange b is omitted to accommodate the pivot-carrying portion c of the plate C, so that the pivot protrudes from out of the border, substantially as shown in Figs. 2 and 3. At d d the plate C is perforated for reception of the screw-threaded lugs e e. The latter enable attachment of the pane by means of the screws f f.

In conforming the pivot or anchor-plate C to the recess g, the lugs e e, and the opening a I provide in an expedient manner a suitable pivot for such doors without materially increasing the cost of construction of such doors.

The plate C, with pivot D, can be cast in the form as shown, and no extra labor or "finishing" is necessary in order to place the plate intermediate the pane and border ready for use.

Doors having pivots which extend horizontally outward from the lower corners thereof can be mounted in brackets E, which are rigidly connected with the oven-fronts, substantially as shown in Fig. 1. The side lugs h of said brackets support the door when opened in horizontal position. Pans or the like can then be placed upon said doors to afford convenience in the handling of such cooking utensils.

What I claim, and desire to secure by Letters Patent, is—

In an oven-door for ranges &c. the combination with the pane and border thereof of an anchor-plate carrying the pivot for said door and being interposed and secured between the said border and pane substantially in the manner as and for the purpose set forth. 85

Signed by me, at Cleveland, Ohio, this 26th day of January, 1899.

HENRY BORN.
